UNITED STATES PATENT OFFICE.

POWELL EVANS, OF PHILADELPHIA, PENNSYLVANIA.

LINK FOR SPRINKLER-HEADS.

1,120,462.

Specification of Letters Patent.

Patented Dec. 8, 1914.

Application filed March 13, 1914. Serial No. 824,461.

To all whom it may concern:

Be it known that I, POWELL EVANS, a citizen of the United States, residing in Philadelphia, Pennsylvania, have invented 5 certain Improvements in Links for Sprinkler-Heads, of which the following is a specification.

One object of my invention is to provide a sprinkler head with a novel form of 10 fusible link whose design shall be such that the solder connecting its members has the form of a pin or rod positioned to resist the stresses set up by the tension exerted on the link under conditions of use;—it being further desired that link elements shall 15 be of such construction that they may be made at a minimum of expense and at the same time efficiently and reliably perform their functions.

20 I further desire to provide a sprinkler head which shall include a novel form of water distributing top portion and which, in addition to being inexpensive to manufacture and assemble, shall satisfactorily 25 spread the water issuing from its base pipe under operating conditions.

These objects and other advantageous ends I secure as hereinafter set forth, reference being had to the accompanying drawings, 30 in which:—

Figure 1 is a side elevation, partly in section, illustrating a sprinkler head constructed according to my invention; Fig. 2 is a front elevation of the head shown in 35 Fig. 1; Fig. 3 is a fusible link in which but two sections are employed; and Fig. 4 is a perspective view of one of the elements forming part of the links shown in Fig. 1 or 3.

40 In the above drawings, 1 represents the externally threaded tubular base of a sprinkler head, and the upper end of this base is shaped to form a valve seat 2 for the reception of a valve 3, having a washer 3^a interposed between it and said seat. Integral with the base 1 is a yoke 4 having the form of a ring which diametrically opposite the center of said base is provided with a threaded opening into which is 45 screwed a bolt 5. This latter is rigidly fixed to a spreader 6 having the form of a disk of sheet material notched at the edges to form a series of teeth 7, and is provided with a series of perforations 8 shown in dotted 50 lines in Fig. 2. It is to be noted that the

teeth of this spreader, in addition to being turned down toward the yoke or main portion of the sprinkler so as to form a concave structure, are individually cupped or made concave with a double curved surface 60 directed toward the outlet, as indicated in the drawings.

Connecting the valve 3 and the bolt 5 are a pair of levers 9 and 10, of which the first has one arm entering a depression in 65 the center of the top of the valve 3 and also has a second arm designed to fit into a recess of one arm of the lever 10. A second arm of this latter fits into a concavity in the lower end of the bolt 5. Each 70 of the levers 9 and 10 has a relatively long laterally projecting third arm and both of said arms lie within a vertical plane having their outer ends formed to receive the elements of a fusible link.

75 In that form of my invention shown in Figs. 1 to 3 inclusive, this link is composed of three elements in the form of three substantially parallel plates of similar construction, although the central plate 11 is preferably thicker than either of the outer plates 12 and 13. One characteristic feature of 80 this fusible link consists in the provision of each of its elements with two series of oppositely projecting, relatively narrow angular 85 portions 14 and 15, which may be formed in any of a number of ways, as, for example, by pressing them up from flat material or by forming the elements of sections of rolled strip material, in which one set 14 of these 90 projecting angular parts is formed as a projecting rib. Thereafter the remaining parts are formed by cutting the strip material into lengths of suitable size, slitting them either before or after the cutting operation 95 and finally pressing out the second set 15 of angular parts. In any case, the projecting angular portions 14 of one element of the fusible link fit between the oppositely projecting angular portions 15 of another element, 100 so that they lie parallel with and immediately adjacent the angular portions 14 of the latter, from which, however, they are spaced a predetermined distance by means of circular projecting lugs or pressed out 105 portions 16.

With the construction described, the parts 14 of the three elements 11, 12 and 13, Fig. 1, or of the elements 11 and 12, Fig. 2, are all 110 parallel and immediately adjacent each other,

as are also all of the angular portions 15 of said elements, and it is to be noted that said portions are so proportioned that when the elements are assembled as shown in Fig. 1, there is a continuous passage-way 20 extending laterally through the link from one side to the other in a line at right angles to its longitudinal center line.

Under conditions of use, the elements are connected by a body of solder having a relatively low but predetermined fusing point and this fills the spaces caused between the elements 11, 12 and 13 by the projections 16. The solder also takes the form of a continuous straight bar or rod, extending from one side or edge of the link to the other through the intermeshing projecting portions 14 and 15, and effectually keys together the elements of the link. Obviously, the bar or rod 20 of solder is integral with the films or plates of solder lying between the link elements and aids in resisting the tension stress to which the link is subjected. Both of the elements 12 and 13 are provided with openings 17 adjacent one end for the reception of the long arm of one of the levers as 10, while the third element 11 likewise has an opening 18 for the reception of the long arm of the second lever 9.

If desired, I may employ that form of the invention shown in Fig. 3, although for most cases that of Fig. 1 is preferable.

I claim:

1. A fusible link consisting of a plurality of intermeshing elements; and a bar of relatively fusible material extending through the intermeshing portions of said elements to lock them together.
2. A fusible link consisting of a plurality of elements, of which at least one is provided with a portion projecting into the other; with a body of relatively fusible ma-

terial extending into said projecting portion to lock it to the second element.

3. A fusible link consisting of a plurality of plates each having at least one projecting portion extending into another plate; with a body of relatively fusible material extending through said projecting portions to lock the elements together.

4. A fusible link consisting of a plurality of elements, of which at least one is provided with a bent out strip extending into another plate; with a body of fusible material extending through the passage between the strip and the body of the adjacent element to lock together said elements.

5. A fusible link consisting of a plurality of elements, each having a plurality of bent out strip portions; with a bar of fusible material extending through the channels formed by said bent out strip portions to lock the elements together.

6. A fusible link consisting of a plurality of plates each having two series of bent out strip portions respectively projecting in opposite directions and intermeshing with those of the other elements; with a body of relatively fusible material extending through said intermeshing strip portions to lock the elements together.

7. A fusible link consisting of a plurality of intermeshing elements; and a body of relatively fusible material connecting the adjacent faces of said elements and extending through their intermeshing portions to lock them together.

In testimony whereof, I have signed my name to this specification, in the presence of two subscribing witnesses.

POWELL EVANS.
